(22) Filed: **Mar. 28, 2001**

(57) **CLAIM**

(30) **Foreign Application Priority Data**

The ornamental design for an interface device for electronic computer, as shown.

Nov. 10, 2000 (JP) 2000-032093
Nov. 10, 2000 (JP) 2000-032094

(51) LOC (7) Cl. **14-02**

DESCRIPTION

(52) U.S. Cl. **D14/439**; D14/433

FIG. 1 is a front perspective view of an interface unit for a computer showing my new design;

(58) Field of Search D14/432, 433,

FIG. 2 is a rear perspective view thereof;

D14/436, 242, 357; D13/184, 199, 162;

FIG. 3 is a front elevational view thereof;

360/99.01-99.12; 361/690-696, 728-736;

FIG. 4 is a rear elevational view thereof;

379/142.15

FIG. 5 is a left side elevational view thereof;

FIG. 6 is a right side elevational view thereof;

FIG. 7 is a top plan view thereof; and,

FIG. 8 is a bottom plan view thereof.
